UNITED STATES PATENT OFFICE

FRANCIS MURPHY, OF NEW YORK, N. Y., ASSIGNOR TO BIGELOW SANFORD CARPET CO.,
INC., A CORPORATION OF MASSACHUSETTS

DESIGN FOR A CARPET

Application filed October 21, 1932. Serial No. 45,435. Term of patent 7 years.

To all whom it may concern:

Be it known that I, FRANCIS MURPHY, a citizen of the United States, residing at New York, in Bronx County and State of New York, have invented a new, original, and ornamental Design for a Carpet, of which the following is a specification, reference being had to the accompanying drawing, forming part thereof.

The drawing illustrates a portion of a carpet showing my design.

The dot and dash lines define the unit of the design. The upper right hand corner of the unit designated "A", is repeated at the lower left hand corner designated "B", while the upper left hand corner of the unit designated "C", is repeated at the lower right hand corner, designated "D".

I claim:

The ornamental design for a carpet substantially as shown and described.

FRANCIS MURPHY.
